CLAIM

The ornamental design for a handheld computing device housing, as shown and described.

DESCRIPTION

FIG. 1 is a front perspective view of a handheld computing device housing showing the new design;

FIG. 2 is a back perspective view thereof;

FIG. 3 is a front elevational view thereof;

FIG. 4 is a back elevational view thereof;

FIG. 5 is a bottom plan view thereof;

FIG. 6 is a top plan view thereof;

FIG. 7 is a left side elevational view thereof; and,

FIG. 8 is a right side elevational view thereof.

The broken lines shown in the drawings depict portions of the handheld computing device housing that form no part of the claimed design.

1 Claim, 6 Drawing Sheets
